UNITED STATES PATENT OFFICE.

HENRY SAWYER, OF ARCTIC CENTER, RHODE ISLAND.

DRILL-BRACE.

1,124,663.

Specification of Letters Patent.

Patented Jan. 12, 1915.

Application filed January 27, 1914. Serial No. 514,807.

To all whom it may concern:

Be it known that I, HENRY SAWYER, a citizen of the United States, residing at Arctic Center, in the county of Kent and State of Rhode Island, have invented certain new and useful Improvements in Drill-Braces, of which the following is a specification.

The object of this invention is to provide a drill brace adapted for a wide range of utility in machinists' and carpentry work and wherein the brace may be either used as a portable tool or connected up to a stand to operate against work mounted upon a work-rest.

My improved drill brace has other features and objects which will be more fully described in connection with the accompanying drawings, and which will be more particularly pointed out and ascertained in and by the appended claims.

In the drawings:—Figure 1 is a view in elevation illustrating the device of my invention attached to a frame stand provided with a work-rest. Fig. 2 is a vertical sectional view on line 2—2 of Fig. 1. Fig. 3 is a view in elevation of a chuck shaft. Fig. 4 is a view of one end thereof. Fig. 5 is a view of the other end thereof. Fig. 6 is a sectional view of a portion of the handle sleeve structure showing the manner of journaling a crank driven shaft therein. Fig. 7 is a view in elevation of an end thrust bearing for a crank driven shaft. Fig. 8 is a sectional view on line 8—8 of Fig. 2. Fig. 9 is a bottom plan view of the chuck. Fig. 10 is a sectional view of a timer.

Like characters of reference designate similar parts throughout the different figures of the drawings.

The device of my invention may be employed in connection with a stand having a body portion 1 from which brace-supporting arms 2 and 3 extend, near the upper portion thereof and which is provided with an arm forming a work-rest, as indicated at 4. The stand 1 may be secured to any form of support 5 by means such as bolts 6.

Referring more particularly to my improved drill brace, 7 designates a breast sleeve having a breast support 8 which latter is adapted for use when the brace drill is used as a portable mechanism. The breast sleeve 7 is provided with ears 9 adapt-

ed to be connected by bolts 10 with ears 11, 55 which latter are formed on the terminal end 12 of the arm 2. The terminal end 12 is shaped to embrace the sleeve 7 so that the ears 9 and 11 can be disposed in abutting relation for connection by bolts 10.

A crank-driven shaft 13 is journaled in the breast sleeve 7 and the upper end of the shaft 13 abuts against an end thrust bearing 14, of the anti-friction type, having anti-friction balls 15 and being suitably secured to the breast sleeve 7. Below the breast sleeve 7 I mount a gear 16 upon the shaft 13, by means such as set screw 17, and below the gear 16 the shaft 13 is reduced, as at 18, and a shoulder 19 is formed 70 at the point of reduction. A chuck shaft 20, is socketed, as at 21, to sleeve the reduced end 18 and the latter is non-rotatably but slidably connected with the chuck shaft 20 by means which may comprise a key or 75 feather 22 on the reduced end 18 and a keyway 23 in the shaft 20. The chuck shaft 20 is exteriorly threaded as indicated at 24 and the lower end 25 thereof is of polygonal cross-section for attachment thereto of 80 a chuck 26. I have shown the chuck 26 provided with a set screw 27 for engagement against the polygonal end 25.

A handle sleeve is indicated at 28 and the upper end rotatably fits a hub 29 on gear 16 85 and the sleeve 28 loosely surrounds the threaded chuck shaft 24. A handle 30 is shown formed integral with the sleeve 28 and projects laterally therefrom as indicated in Fig. 1. The sleeve 28 is provided with a bearing 31, formed integral with the sleeve and connected by an arm 32. The sleeve 31 is provided with ears 33 adapted to abut ears 34 formed on the terminal end 35 of supporting arm 3. The terminal end 90 35 is adapted to embrace the bearing 31 and the ears 34 and 33 are shown connected by bolts 36.

A crank shaft 37 is journaled in a bearing 38 which may be formed at the terminal end of an arm 39 formed integral with and projecting upwardly from the bearing 31. On the crank shaft 37 I fix a bevel gear 40 which meshes with bevel gear 16 so as to transmit rotary motion to the driven shaft 100 13. A crank 41 is fixed to the outer end of the crank shaft 37, by means of a nut 42. The inner end of the crank shaft 37 extends

through a bearing 43, formed on the sleeve 28, and I interpose an anti-friction thrust bearing 44, in the bearing 43, in a manner so that the anti-friction balls 45 will engage 5 the cylindrical shaft 37 and a conical head 46, formed thereon. When the nut 42 is tightened so as to jam the crank 41 against the bearing 38, the flared or conical end 46 will be engaged against the balls 45.

- 10 A chuck feeding mechanism is provided for screw threaded engagement with the chuck shaft to axially advance the same upon rotation thereof and said chuck feeding mechanism may comprise a nut 47 having a reduced sleeve 48 in threaded engagement with the chuck shaft with the sleeve 48 extending into the bearing 31 to maintain the chuck shaft in position, axially. The chuck feeding mechanism is provided 15 with an arm 49 which extends upwardly about the wheel 40 and is apertured to be supported on the crank shaft 37, as indicated at 50.

With the device of my invention disposed 20 in the manner shown in Fig. 1, it will be seen that rotation of the crank 41 will not only rotate the chuck shaft but will cause the same to be axially advanced with respect to the driving shaft 13 to advance the 25 tool, which may be a drill or auger or screw driver or other form of tool, toward the work mounted upon arm 4. After the tool has been operated, it will be seen that rotation of the crank in a direction opposite 30 from a driving direction, will rotate the tool out of the work and axially withdraw the tool from the work.

If it is desired to use the device of my 35 invention as a portable brace drill, it will merely be necessary to remove bolts 10 and 36 whereupon the device will be held for operation in substantially the same manner as an ordinary brace drill.

While I have herein shown and described 40 one specific form of my invention I do not wish to be limited thereto except for such limitations as the claims may import.

I claim:-

1. In a hand drill, a stand, a breast sleeve 45 fixed to said stand, a handle sleeve fixed to said stand, a crank-driven shaft rotatable in said sleeve, a chuck shaft telescoping said driven shaft and non-rotatably connected therewith, and a chuck feeding means for feeding said chuck shaft on rotation thereof.

2. In a hand drill, a stand, a breast sleeve fixed to said stand, a handle sleeve fixed to said stand, a crank-driven shaft rotatable in said breast sleeve, a chuck shaft non-rotatably but slidably connected with said driven shaft and having a chuck, and chuck feeding means for feeding said chuck shaft on rotation thereof by said driven shaft.

3. In a hand drill, a stand, a breast sleeve 50 fixed to the stand, a handle sleeve fixed to the stand, a crank-driven shaft rotatable in said breast sleeve, a chuck shaft slidably and non-rotatably connected with said driven shaft and provided with screw 70 threads, a chuck carried by said chuck shaft, and threaded chuck feeding means for engaging the threads in said chuck shaft to advance the latter on rotation thereof.

4. In a hand drill, a fixed sleeve, telescoping driven and chuck shafts non-rotatably connected with each other and rotatably mounted in said sleeve, and means associated with said sleeve and with said chuck shaft for feeding the latter upon rotation thereof. 80

5. In a hand drill, a fixed upper sleeve, a fixed lower sleeve, a driven shaft in said upper sleeve, a gear fixed to said driven shaft and supported by said lower sleeve, an exteriorly threaded chuck shaft telescoping 85 and non-rotatably connected with said driven shaft and extending through said lower sleeve, a threaded chuck feeding device journaled in said lower sleeve and having threaded engagement with said chuck shaft to advance the same upon rotation thereof, a crank shaft journaled on said lower sleeve and connected with said chuck feeding device to hold the same against rotation, and a gear on said crank shaft meshing with the gear on said driven shaft to operate said chuck shaft. 95

6. In a hand drill, a fixed sleeve, an exteriorly threaded chuck shaft extending therethrough, a crank shaft journaled in 100 said sleeve, a chuck feeding device journaled in said structure and having threaded connection with said chuck shaft to advance the latter upon rotation thereof and engaging said crank shaft whereby the chuck feeding device is held against rotation in said sleeve, and means for imparting rotation to said chuck shaft upon rotation of said crank shaft. 105

7. In a hand drill, a stand having supporting arms and a work-rest arm, sleeves fixed to said supporting arms, a driven shaft rotatable in one of said sleeves and a chuck shaft rotatable in the other of said sleeves and having telescoping non-rotative connection with said driven shaft, a chuck feeding device having threaded engagement with said chuck shaft and being journaled in one of said sleeves non-rotatably to advance the chuck shaft upon rotation thereof by said driven shaft; and a chuck mounted on said chuck shaft. 110

8. In a hand drill, a fixed sleeve, an exteriorly threaded chuck shaft extending through said sleeve and having a socket in one end thereof, a chuck on the other end of said shaft, means for rotating said chuck shaft, and a chuck feeding device non-ro- 120 125

tatably journaled in said sleeve and having threaded engagement with said chuck shaft to advance the same as it is rotated.

9. In a hand drill, a fixed upper sleeve, a driven shaft therein, an end thrust bearing in said sleeve engaging the end of said driven shaft, a lower sleeve, an exteriorly threaded chuck shaft in the lower sleeve and having driven connection with said driven shaft, and a chuck feeding device non-rotatable

fixed in said lower sleeve and having threaded engagement with said chuck shaft to advance the same as it is rotated.

In testimony whereof I affix my signature in presence of two witnesses.

HENRY SAWYER.
